(57) **CLAIM**

The ornamental design for combined power and data component mounted on a movable carriage and cover, as shown and described.

DESCRIPTION

FIG. 1 is a perspective view of the combined power and data component mounted on a movable carriage and cover in a closed configuration, and showing my new design;

FIG. 2 is a left side view thereof;

FIG. 3 is a right side view thereof;

FIG. 4 is a front view thereof;

FIG. 5 is a back view thereof;

FIG. 6 is a top plan view thereof; and,

FIG. 7 is a bottom plan view thereof.

FIG. 8 is a perspective view of the combined power and data component mounted on a movable carriage and cover in an open configuration, and showing my new design;

FIG. 9 is a left side view thereof;

FIG. 10 is a right side view thereof;

FIG. 11 is a front view thereof;

FIG. 12 is a back view thereof;

FIG. 13 is a top plan view thereof; and,

FIG. 14 is a bottom plan view thereof.

In the drawings, the broken lines are for the purpose of illustrating environment only and form no part of the claimed design.

1 Claim, 6 Drawing Sheets
